MERCHANTISING RACK

Samuel D. Heed, Cincinnati, Ohio, and Elmer C. Hake, Park Hills, Ky., assignors to The Gibson Art Company, Cincinnati, Ohio, a corporation of Ohio

Application December 3, 1940, Serial No. 368,378

8 Claims. (Cl. 312—120)

This invention relates to merchandising racks of the type which are used in retail stores for the display, storage and merchandising control of greeting cards of various designs, sizes, prices and purposes.

It is an object of our invention to provide in connection with such display racks means for indicating when the supply of any particular style, price or purpose of cards is nearly exhausted so that re-ordering becomes necessary. In the merchandising of greeting cards it is desirable to keep on hand a certain stock of each particular style, price and purpose of card and by virtue of experience, the store merchant will re-order cards when the supply on hand attains a certain value. The examination of each pigeon hole or compartment in a display rack or any other stock storage device to determine the number of cards in stock is tedious and uncertain.

With the above considerations in mind it is an object of our invention to provide means for automatically indicating when the supply of cards of any particular purpose and price on hand has reached the minimum number at which it has been determined advisable to re-order. Another object of our invention is to provide an arrangement, as above outlined, which will be substantially fool-proof in operation, which will be extremely simple and which will not materially add to the cost of merchandising or display racks.

A further object of our invention is to provide a combination display rack and greeting card container wherein the surplus stock of the greeting card is held in the container directly back of the displayed card so that by pivoting the container one or more new cards may be removed and placed in display position in front of the container when the original card has been sold.

A further object of our invention is to provide a pivoting display rack and container which permits the individual removal of each container from the rack without disarranging other containers and other displayed cards, and which while being pivotable and removable with extreme ease is locked in position in the rack so that the inversion of the complete display rack in shipping will not permit the individual containers to fall out.

Reference is now made to the drawings forming a part hereof and in which:

Figure 1 is a front elevation of a display rack embodying our invention.

Fig. 2 is a cross sectional view taken on the line 2—2 of Fig. 1.

Fig. 3 is a perspective view as seen from the rear of a greeting card container.

Fig. 4 is a view similar to Fig. 3 showing the other side of the container.

Fig. 5 is a perspective view of a modification of our invention.

6. Fig. 6 is a plan view of a stock or merchandising ticket which may be used with the invention.

Fig. 7 is a partial perspective view of the front of a container showing how a card indicating the lot number may be held in position.

10 Fig. 8 is a front elevation of a modified form of our greeting card container illustrating the locking feature of the pivot mechanism.

Fig. 9 is a cross section of our greeting card container shown in Fig. 8 taken on the line 15 9—9 of Fig. 8.

Fig. 10 is a cross section of our modified form of greeting card container taken on the section line 10—10 of Fig. 9.

20 Fig. 11 is a cross section of our modified form of greeting card container mounted on the rack and in its locked position.

Fig. 12 is a cross section of our modified form of greeting card container mounted on its rack in its tilted and unlocked position.

25 Fig. 13 is a perspective view of a portion of the rack for holding our modified container.

Briefly in the practice of our invention, we provide a plurality of containers of a size and shape to contain a number of greeting cards of a particular price and purpose. The individual containers are arranged for pivotal movement about their support so that access may be had to the containers to remove therefrom or place therein greeting cards. Within the containers

30 we provide a ticket holding device which is pivotable and which loosely holds a ticket which may carry on it a lot number or serial number or style number or the like. A number of cards equal to the minimum, at which point re-ordering is necessary, is placed in front of the pivoted member and the remaining cards in stock are placed behind the pivoted member, the pivoted member being thus held in erect position with the ticket therein.

35 When the number of cards behind the pivoted members becomes exhausted, the pivoted member pivots to a position in which the ticket drops out and falls into a drawer so that at any time the drawer is opened the tickets found in the drawer will indicate what price and

40 purpose of greeting cards have reached the minimum in the containers and must be re-ordered.

45 Referring now more particularly to the drawings, we have shown a rack comprising side wall members 10, a rear wall member 11 and a front strip 12. The side walls are preferably of gen-

erally triangular shape so that the display slopes rearwardly. Fixed between the side walls 10 and extending transversely of the rack are a number of L-shaped dividing bars indicated in the figures generally at 13. Mounted on the bars 13 are angle strips 14 which, as will be pointed out hereinafter, provide a mounting for the containers.

The containers, as shown in Figs. 3 and 4, may be made of sheet metal or any desired material and comprise box-like structures indicated generally at 15 having an extended front face 16. Struck out from the front face 16 are the lugs 17 by which the containers are held by the loose pivotal engagement of said lugs 17 over the angle members 14 as most clearly shown in Fig. 2. It will be observed that the member 13 is rabbed, as indicated at 18, to provide a seat for the free end of the front face 16. Each container may be positioned by inserting it in between two dividing bars 13 and engaging the members 17 over the channel 14 as indicated near the top of Fig. 2. Upon releasing the container it will swing to the position shown for the other containers 13 in Fig. 2. It will be observed that the front face 16 of the containers may have a flange portion 19 and greeting cards may be placed on display in front of the containers resting upon the members 18 and leaning back against the container as shown in Fig. 2 at 20. The members 19, of course, serve to maintain the cards on display in alignment. As shown in Fig. 7, lugs 21 may be struck out from the member 19 to provide means for holding a ticket 22 carrying the lot number or style number which will thus have visibility from the front of the rack.

The pivoted ticket holding device may take several forms of which we have illustrated two. As shown in Fig. 3, we may provide a rod 23 extending across the container at any desired position. Pivoted upon the rod 23 is a ticket holder 24 made from sheet metal or the like and having the flanges 25 arranged to loosely hold a ticket in position. In practice, as shown in Fig. 2, any desired number of cards which is to constitute the minimum on hand before re-ordering is placed in the container in front of the rod 23. The remaining cards are placed behind the bar 23 with the member 24 in its upright position and containing a ticket as shown in the top and bottom containers in Fig. 2. It will be clear that tilting of the container forward to remove therefrom a card will in no way affect the member 24, it being understood that cards are removed first from the rear of the container. When the last card 20a behind the rod 23 is removed, as shown in the second container from the top in Fig. 2, it will be clear that when this container returns to its normal tilted position, the pivoted member 24 is free to pivot downwardly through the cut-out portion 15a of the container 15. In this position, it will be clear that the ticket 26 is free to fall out as shown in Fig. 2.

As shown in Fig. 2, we provide a sloping chute or the like at 27 whereby the tickets 26 as they fall from the members 24 will be guided to a drawer 28 conveniently mounted at the bottom of the display rack near the front. An accumulation of dropped tickets is indicated at 29. It will be clear that when the drawer is withdrawn the tickets 26 contained in the drawer will indicate accurately just which prices and purposes

of cards must be re-ordered without the necessity of examining each rack or each container.

In Fig. 5 we have shown a modified structure wherein the member 24 and the rod 15 form a part of a baffle member 30 having flanges 31. With this construction the pivoted member is, of course, not integral with the container and may be removed if desired or its position within the container may be altered since the baffle 30 will fit freely in the container 15. The operation of this modification is exactly the same as described above.

Figs. 8 to 13 inclusive show a modified form of our greeting card container. In this instance the rack or strip 14a contains a slot 40, while the front face 16 of the container has a downwardly struck-out projecting finger 41 in addition to the lugs 17. Projecting from the front face 16 and below the end of the finger 41 is an abutment 42. The abutment 42 is spaced from the end of the finger 41 at least a distance as great as the depth of the slot 40.

In such a way the container is positioned on the rack 14a with the finger 41 projecting through the slot 40 as is shown in Fig. 11.

Furthermore, it is apparent that the container may be tilted forward as in Fig. 12 and while in that position may be removed by drawing the containers forward so that the finger 41 will come out of the slot 40 before the abutment 42 contacts the strip or rack 14a.

The ticket holder 24 is hinged or pivoted to the strip 44 secured to the ends of the container and which is cut out as at 45, so as to present a narrow portion at the point of pivot. By this construction, as a number of cards are placed in front of the strip 44 they will contact the edge portion of the strip and will not tend to bend the pivot line of the ticket holder, as is apparent in Fig. 11.

It will be clear that numerous modifications will suggest themselves to one skilled in the art, and such modifications may be made without departing from the spirit of the invention. We, therefore, do not intend to limit ourselves otherwise than as pointed out in the claims which follow.

Having thus described our invention what we claim as new and desire to secure by Letters Patent is:

1. A display device for greeting cards and the like comprising a rack and at least one greeting card container pivotally mounted in relation to said rack, a ticket holding device pivotally mounted in said container in a position where greeting cards may be placed in said container both in front of and behind said device and a ticket loosely held in said device whereby when the supply of cards behind said device is exhausted, said device is free to pivot and said ticket is free to fall out.
2. A display device for greeting cards and the like comprising a rack and a number of greeting card containers pivotally mounted in relation to said rack, a ticket holding device pivotally mounted in each of said containers in a position where greeting cards may be placed in said containers both in front of and behind said devices and tickets loosely held in said devices whereby when the supply of cards behind said devices is exhausted, said devices are free to pivot and said tickets are free to fall out and means for piling together tickets discharged from said containers.
3. In combination with a container for greeting cards and the like, a ticket holding device provided in said container in a position in which cards may be placed in said container both in

front of and behind said device, said device in one position being adapted to retain a ticket and said device adapted to be retained in said position by greeting cards behind said device, said device in another position permitting said ticket to fall therefrom by gravity and said device being arranged to pivot to said other position when there are no cards behind said device.

4. In combination with a container for greeting cards or the like, a bar extending transversely of said container intermediate the front and rear thereof, a ticket holding device pivoted to said bar, the rear face of said container being cut away to permit said device to pivot to a downwardly extending position.

5. In combination with a container for greeting cards or the like, a bar extending transversely of said container intermediate the front and rear thereof, a ticket holding device pivoted to said bar, the rear face of said container being cut away to permit said device to pivot to a downwardly extending position, said bar being narrower at the pivot point so that cards contacting said bar will not interfere with the pivoting action.

6. In combination with a container for greeting cards and the like, a baffle element removably positioned within said container and a ticket holding element pivoted to said baffle element, the rear face of said container being cut away to

permit said ticket holding element to pivot to a downwardly extending position.

7. In combination, a container for greeting cards or the like and means for indicating when the supply of cards in said container has reached a predetermined minimum, said means comprising a member for holding a ticket within the container in a certain position of said member and means whereby said member is adapted to be held in same position by a card or cards in addition to said predetermined minimum and to be swung by gravity to a position in which the ticket will be discharged therefrom by gravity when said card or cards have been removed, whereby the discharged ticket will serve to indicate that said predetermined minimum has been reached.

8. The combination of a merchandising device or the like consisting of a display rack and a container for greeting cards and the like positioned behind said rack, said container being mounted in said device for pivotal movement, and signal means in said container adapted to be held against operation by a card in said container and to be released for operation by gravity upon the removal therefrom of said card for indicating at a place distant from said container when no card remains in holding position.
